IMITATION HINGE

La Verne E. Clayton, Rockford, Ill., assignor to Amerock Corporation, Rockford, Ill., a corporation of Connecticut

Filed May 26, 1969, Ser. No. 17,328

Term of patent 14 years

Int. Cl. D8—03

U.S. Cl. D8—202

FIG. 1 is a front view of an imitation hinge incorporating my new design.

FIG. 2 is an enlarged top view of the imitation hinge.

FIG. 3 is an enlarged side view as seen from the right in FIG. 1.

FIG. 4 is an enlarged sectional view taken along the line 4—4 in FIG. 1.

FIG. 5 is an enlarged perspective view of the imitation hinge.

I claim:

The ornamental design for an imitation hinge, as shown.
